CHOKE MEANS FOR TWO-CYCLE ENGINES

Filed March 21, 1929

Owen H. Spencer
Inventor

UNITED STATES PATENT OFFICE

OWEN H. SPENCER, OF INDIANAPOLIS, INDIANA

CHOKE MEANS FOR TWO-CYCLE ENGINES

Application filed March 21, 1929. Serial No. 348,905.

This invention relates to choke mechanisms for internal combustion engines, and is designed primarily for use in connection with two cycle engines, and one feature of 5 the invention is the provision of a choke valve between the cylinder feeding mechanism and the cylinders of the engine for regulating the admission of fuel to the cylinders.

10 A further feature of the invention is the provision of means for operating the choke valve in unison with the valve for the carbureter.

15 A further feature of the invention is the provision of means for utilizing the back pressure created by the closing of the choke valve for regulating the speed of the engine, as when idling.

20 Other objects and advantages will be hereinafter more fully set forth and pointed out in the accompanying specification.

In the accompanying drawing which forms a part of this application,

25 The figure is a vertical sectional view thru a two cycle engine with parts broken out.

Referring to the drawing the numeral 1 indicates the cylinder of an engine, preferably of the two cycle type, 2 indicates the crank case therefor and 3 indicates the piston 30 for the cylinder, said piston being operated in the usual manner from a crank 4, thru the medium of connecting rod 5.

The cylinder 1 has an exhaust port 6 at its lower end and at one side thereof, while 35 a fuel supply port 7 is arranged substantially on the opposite side of the cylinder and substantially in alignment therewith, and communicating with said fuel supply port 7 is a fuel conveying passage 8, the lower 40 end of which communicates with a charger chamber 9.

Mounted within the chamber 9 is a fuel 45 charger 10 comprising a circular body portion 11 eccentrically and rotatably mounted therein, said body portion having a plurality of radially arranged slots 12, in which are mounted longitudinally movable blades 13, the outer ends of which travel against the peripheral wall of the charger chamber 9.

50 Communicating with the charger chamber

9, thru the medium of a port 14, is a carbureter 15, of the usual or any preferred structure, thru which fuel is supplied to the charger chamber and thence thru the fuel passage 8 to the cylinder 1.

55 Mounted in the neck 16 of the carbureter 15 is a butterfly valve 17, to which is attached an operating lever 18. Any suitable means

may be attached to the lever 18 and extended 60 to a point in convenient reach of the operator. In addition to the butterfly valve 17 used for regulating the flow of gaseous fuel thru the carbureter, a choke valve 19 is positioned in the fuel passage 8, said choke valve

65 having a lever 20 for operating the same, and in order to operate the choke valve in exact unison with the butterfly valve 17, a rod 21 is extended from the lever 18 to the lever 20, so that as the butterfly valve is opened or closed, the choke valve will be correspondingly 70 opened or closed.

The object of the choke valve 19 is twofold, to regulate the flow of fuel thru the passage 75 8, and to create a back pressure against the charger 10, which acts as a brake to check the momentum of the engine as when running idle, or when the engine is throttled down, by which arrangement the engine is adapted to sensitive speed and power control.

The choke valve is very essential, owing to 80 the fact that the fuel is entered into the fuel passage 8 with considerable force by the charger structure 10 and by operating it in unison with the butterfly valve 17, said choke valve will be opened and closed in exact 85 unison with the butterfly valve, and as said choke valve begins to close, a back pressure against the charger 10 will be set up and act as a braking medium against the charger and thru the charger to the engine, to reduce the 90 momentum of the engine, the charger 10 being driven directly from the engine.

95 While the description and drawing illustrate in a general way certain instrumentalities which may be employed in carrying the invention into effect, it is evident that many modifications may be made in the various details without departing from the scope of the appended claims, it being understood 100

that the invention is not restricted to the particular examples herein described.

I claim as my invention:

1. In a choke valve mechanism for an engine, the combination with a cylinder, a fuel passage connecting with said cylinder, a charging mechanism connecting with said fuel passage, a carbureter connecting with said charging mechanism, and a valve associated with said carbureter between said carbureter and charging mechanism, of a choke valve intersecting said fuel passage between said cylinder and charging mechanism, whereby the back pressure created by closing said choke valve will not be directed against the carbureter, and means for connecting said choke valve with the valve of the carbureter, whereby when the carbureter valve is moved to open or closed position the choke valve will be simultaneously moved to open or closed position.
2. In a choke mechanism for an engine, the combination with a cylinder, a fuel passage connecting with said cylinder adjacent the lower end of the cylinder, a charging mechanism connecting with said passage, a carbureter connecting with said charging mechanism, a butterfly valve associated with said carbureter and between said carbureter and charging mechanism, and a lever for operating said valve, of a choke valve located in said fuel passage between said cylinder and charging mechanism, whereby the back pressure created by closing said choke valve will not be directed against the carbureter, a lever for operating said choke valve, and a rod connecting the lever of the butterfly valve with the lever of the choke valve, whereby said choke valve will be operated when the butterfly valve is operated.

In testimony whereof, I have hereunto set my hand on this the 14th day of March, A. D. 1929.

OWEN H. SPENCER.
